UNITED STATES PATENT OFFICE.

ANGUS G. McCORMACK, OF PORT ARTHUR, ONTARIO, CANADA.

GRAIN-CAR DOOR.

1,106,395.

Specification of Letters Patent. Patented Aug. 11, 1914.

Application filed August 30, 1912. Serial No. 717,908.

To all whom it may concern:

Be it known that I, ANGUS G. McCORMACK, of the town of Port Arthur, in the district of Thunder Bay, in the Province of Ontario, Canada, have invented certain new and useful Improvements in Grain-Car Doors, of which the following is the specification.

My invention relates to improvements in grain car doors and the object of the invention is to devise a strong, durable and compact door which is non-leakable, which may be attached to an ordinary car without weakening the car posts, which may be readily raised to its open position in proximity to the car roof and which will automatically drop to its closed position when released, and it consists essentially of a vertical guideway located at each side of the car door and comprising vertical series of guide sections having a front slot opening of different widths and terminating at its upper end in a peculiarly constructed pocket, and a car door comprising vertically arranged sections having runners at each end thereof adapted to fit into the guideways in which the runners are moved from a section having a front slot opening of less diameter to a section having a front slot opening of greater diameter in the guideway so that when the upper end of the runner enters the pocket the major portion of the runner is capable of being swung outwardly through the front slot opening of the upper section of the vertical guideway, and a series of bracing truss rods extending across the door at suitable distances apart as hereinafter more particularly explained by the following specification.

Figure 1 is a general perspective view of my car door partially broken away and in section and looking from the inside of the car. Fig. 2, is a horizontal section through Fig. 1. Fig. 3, is a vertical section through Fig. 1 showing the door in its closed position by full lines and in its open position by dotted lines. Fig. 4, is a vertical section through the grain door. Fig. 5, is a perspective detail of one of the guide ways. Fig. 6, is a perspective detail of a pair of runners. Fig. 7, is an enlarged perspective view of the upper portion or pocket of the guide way. Fig. 8, is a vertical section through the pocket. Fig. 9, is a cross section through the guide way and runners on line $x-y$ Fig. 3. Fig. 10, is a similar view to Fig. 9 on

line $x'-y'$ Fig. 3. Fig. 11, is a similar view to Figs. 9 and 10 on line x^2-y^2 Fig. 3.

In the drawings like letters of reference indicate corresponding parts in each figure. 60

The car door frame comprises side posts A' and A², sill A³ and the top plate A⁴.

B is the floor of the car and C is the sheeting forming the wall of the car.

Vertical guide ways are secured by bolts 65 D' to the side posts A' and A² of the car door. The guide ways comprise a vertical portion D², having a narrow slot opening D¹², a vertical portion D³ at the upper end of the guide having a wide front slot 70 opening D¹³ and an intermediate portion D⁴, having a front slot opening D¹⁵ of greater width than the slot opening of the portion D² and of less width than the slot opening of the portion D³, and a supplemental guide 75 way D¹⁴.

D⁵ is a pocket located at the upper end of each of the guide ways. The front face of the pocket is formed arc shaped with a vertical slot D⁶. 80

D⁷ and D⁸ are orifices formed on the opposite face of the pocket for a purpose which will hereinafter appear.

D⁹ are arc shaped dividing tongues located intermediately of the height of the 85 interior of the pocket D⁵ to each side of the slot D⁶. The pocket D⁵ is preferably formed separate from the guide ways and is connected thereto by means of dowel pins D¹⁰.

The grain car door comprising the lower 90 section E' and the upper section E² provided with end metallic vertical plates E³ connected to the door by bolts E⁴. The metallic plates E³ prevent the door being secured to the car frame by means of nails 95 or otherwise and thus destroyed.

A runner is secured to each side of the car door section E', and comprising runner sections F¹¹ and F¹². The runner section F¹¹ is provided with flanges F' fitting the 100 narrow portion D² of the guide way. The runner section F¹¹ is also provided with a flanged portion F² above the flanged portion F'. The flange F² fits into the base of the lower end of the intermediate portion D⁴ of 105 the guide way. The runner sections F¹² are secured to the door section E² at each end thereof, on a line with the section F¹¹. The runner section F¹² is provided with flanges F⁴ fitting into the reduced portion D¹⁴ of 110 the guide section D⁴ (see Fig. 10). The runner F¹² is also provided with flanged

portions F^5 of the same width as the flanged portion F^2 slideable within the base or enlarged portion of the vertical guide way section D^4 and F^4 slideable within the upper guide D^3 .

5 F^6 is an enlargement of the flange F^4 designed to strike against the lower end of the pocket D^5 when the door section is raised so as to limit the upward movement of the 10 runner in the guide way D^3 .

15 G is a covering plate secured along the lower edge of the upper door section E^2 . It will be noticed that the plate G curves slightly outwardly and downwardly so as to receive the pressure of the grain in the car tending to force the upper door section E^2 down against the lower door section. By this means the division between the door sections is rendered grain tight.

20 H is a strip of metal extending through an opening in the lower edge of the lower door section E' so as to form a pocket extending inwardly of the car and upon which the pressure of the grain in the car bears so as to force the lower door section down 25 against the floor of the car. This pocket also serves as a means for prying the doors upwardly, a lever or other suitable instrument being inserted in the pocket for that 30 purpose.

35 There are truss rods extending crosswise of the door sections and preferably secured at their ends in the runner F by the nuts I' . By this means the door is stiffened preventing the bulging of the door by grain pressure.

40 In operation when it is desired to empty the car the lower door section is pried upwardly as hereinbefore described so as to relieve the grain pressure in the car. The 45 upper door section is then slid upwardly until the flanged portion F^5 comes opposite the opening in the back place of the pocket piece, and is then tilted so that F^5 engages the bottom edge of the opening. The door section is then swung inwardly into the dotted position shown in Fig. 3 the runner bar flanges passing through the enlarged opening D^{13} of the upper vertical guide section D^3 . The opening D^7 forms a fulcrum in 50 which the door section is turned. Similarly the lower door section E' is carried upwardly until the end of the flange F' of the runner F^{11} strikes against the end of the pocket. In this position when the door 55 is swung outwardly the lower edge of the opening D^8 forms a fulcrum on which the door is swung upwardly. The door sections E' and E^2 are held in their upper position against the roof of the car by any suitable 60 means which it is not necessary here to describe. When such means is released the door sections swing back to the vertical position and drop through the guide ways to their closed position.

65 From this description it will be seen that

I have devised a very simple form of grain car door which will be strong and durable in construction, which may be readily attached to any ordinary form of car and which may be easily raised to the open position and dropped automatically to its closed position.

70 What I claim as my invention is:

1. In a grain car door, the combination with the side posts of the door, of guide ways secured to the door having the front opening thereof increasing in width in successive sections, a pocket having an arc-shaped lower end into which the guide ways lead, a vertical front slot and an arc-shaped cross wall intermediate of its height, grain door sections, runners connected to the door sections and having lateral projections at their upper ends designed to enter the pocket when the door is raised whereby the upper 85 door section is swingably supported on the arc-shape cross wall and the lower section is swingably supported in the arc-shaped lower end of the pocket, the major portion of the runners being rigidly held in the 90 guide-ways in the closed position of the door and designed to swing outwardly through the front of the sections of increased width to the open position, as and for the purpose specified.

95 2. In a grain car door, the combination with the side posts of the door, of guide ways secured to the door having the front opening thereof increasing in width in successive sections, a pocket having an arc-shaped lower end into which the guide ways lead, a vertical front slot and an arc-shaped cross wall intermediate of its height, grain door sections, runners having upper lateral flanged pieces at their upper end and fitting 100 within the guide ways so as to slide upwardly into the pocket and lower flanged portions normally held in the lower guide sections and adapted to swing outwardly 105 through the upper enlarged opening of one 110 of the upper sections of the guide ways when the upper lateral flanged piece has entered the pocket, as and for the purpose specified.

115 3. In a grain car door, the combination with the side posts of the door, of guide ways secured to the door having the front opening thereof increasing in width in successive sections, a groove in the guide way comprising an inner wide portion forming 120 the base of the guide way and an outer grooved portion formed at each side of the vertical opening of the guide way, a pocket having an arc-shaped lower end into which the base of the guide way leads, a vertical 125 front slot and an arc-shaped cross wall intermediate of its height, a grain door comprising sections, side runners secured at each end of each section, lateral flanged pieces at the upper end of each runner fitting 130

within the base or wide portion of the groove of the guide way and having the lateral flanges fitting within the outer groove at each side of the guide way opening whereby when the runner is moved vertically the upper lateral projecting piece is retained in the guide way and carried into the pocket and the lateral flange of the runner is freed so as to swing outwardly

through the enlarged opening of the upper 10 guide way so that the door may be swung in proximity to the roof, as and for the purpose specified.

ANGUS G. McCORMACK.
